DESIGN FOR A DISPLAY PLATE FOR AUTOMOBILES

Marcus A. Gould, New Kensington, Pa.

Application July 30, 1938, Serial No. 78,978

Term of patent 3½ years

To all whom it may concern:

Be it known that I, Marcus A. Gould, a citizen of the United States, residing at New Kensington, in the county of Westmoreland and State of Pennsylvania, have invented a new, original, and ornamental Design for a Display Plate for Automobiles, of which the following is a specification, reference being had to the accompanying drawing, forming part thereof.

Figure 1 is a side elevational view of a display plate for automobiles, showing my new design.

Figure 2 is a perspective view.

Figure 3 is an edge elevational view.

I claim:—

The ornamental design for a display plate for automobiles, as shown.

MARCUS A. GOULD.
